By his Attorney
H. M. Broadwell

UNITED STATES PATENT OFFICE.

HARRY M. BROADWELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

INCLOSED-SWITCH CONSTRUCTION.

1,353,021.

Specification of Letters Patent. Patented Sept. 14, 1920.

Application filed December 13, 1919. Serial No. 344,722.

To all whom it may concern:

Be it known that I, HARRY M. BROADWELL, a citizen of the United States of America, residing at Plainville, Connecticut, have invented a new and useful Inclosed-Switch Construction, of which the following is a specification.

My invention relates particularly to a safety type of switch and the main object is to provide a shield or guard which can be made cheaply and readily assembled and yet which can be securely held in place.

In its simplest form the invention contemplates the employment of lugs or brackets carried by the inner side walls. The shield or guard plate is provided with special tongues adapted to interlock with these lugs by a simple sliding action. One end of the guard plate or shield may be fastened to the end wall of the box in any suitable manner.

Figure 1 is a front view of an inclosed switch construction embodying the improvements of my invention, the cover being open and only a fragment of it shown.

Fig. 2 is a longitudinal sectional view.

Fig. 3 is a perspective view showing fragments of the box and the guard plate or shield separated.

Fig. 4 is a transverse sectional view showing a flanged type of box.

The body 5 of the box is of any suitable construction and may be provided with any suitable type of cover 6.

Any form of switch mechanism, 7 may be mounted in the box. The method of operating the switch is immaterial but it is usual to employ some form of external handle (not shown).

The guard plate or shield 8 is adapted to fit in the upper edge of the box and to cover over all the live parts of the switch leaving only the fuses exposed. To support the shield I have provided lugs or brackets 9-9 which are suitably secured to the inner side walls of the box for instance by means of welding, riveting, or screws and which project toward each other and afford seats for the edges of the shield. At the end of the box is located another lug or bracket 10 which supports the end of the shield.

The sides of the shield are provided with tongues 11 adapted to slide on and interlock

with the lugs 9-9. In the form shown 55 herein these tongues are integral with the shield and are formed by cutting parts of the edges of the shield and bending them down into the plane parallel with the main part of the shield leaving just enough space 60 for receiving the lugs 9-9.

The shield may be secured in place by a single screw 12 or other suitable fastening device or seal.

To assemble the parts it is simply necessary to put the shield into position on the lugs 9-9 and slide it endwise toward the lug 10. The tongues 11-11 slide underneath the lugs 9-9 and when the screw 12 or other fastening device is in place the 70 shield is securely held against movement and the operator is protected from accidental contact with any live part of the switch.

The construction is such that the shield may be located substantially flush with the 75 upper edge of the box and this allows the maximum space in the box for a switch and a maximum clearance.

In the form shown in Fig. 4 the body of the box is provided with flanges 13 around 80 the edge.

It should be understood that I have only shown one form of my invention and that I contemplate that modifications may be made in details of the construction without departing from the spirit or scope of my invention.

I claim:

1. In an inclosed switch construction, the combination of a box, a lug projecting inwardly from the end thereof, lugs projecting inwardly from the opposite sides thereof, and a shield having tongues on the underside adapted to slidably engage the lugs at the sides of the box, and means for securing the end of the shield to the end lug.

2. In an inclosed switch construction, the combination of a box, lugs projecting inwardly from the sides thereof, a shield having tongues at the side edges adapted to slidably engage said lugs by an end-wise movement of the shield, and a single means for securing the end of the shield in place and preventing end-wise movement of the shield.

3. In an inclosed switch construction, the combination of a box, a plurality of lugs projecting inwardly from the inner walls of the box, a shield adapted to be supported

on said lugs and having tongues adapted to slidably engage beneath a plurality of said lugs, and means for preventing end-wise movement of said shield.

5 4. In an inclosed switch construction, the combination of a box, lugs projecting from the inner walls thereof, a shield having

tongues cut from the edges thereof, and having their free ends lying in planes spaced apart from the lower face of the shield and adapted to slidably engage said lugs, and means for securing said shield against movement.

HARRY M. BROADWELL.
